ELECTRICAL CIRCUIT TESTING DEVICE

Warren W. Hannon, Olathe, Kans., assignor to Dit-MCO,
Inc., Kansas City, Mo., a corporation of Missouri

Filed Jan. 22, 1958, Ser. No. 49,358

Term of patent 14 years

(Cl. D26—1)

Fig. 1.

Fig. 2.

Fig. 1 is a perspective view showing the front, top and one end of an electrical circuit testing device, showing my new design; and

Fig. 2 is a perspective view showing the rear and opposite end thereof.

The dominant features of my new design are shown in solid lines in the drawing.

I claim:

The ornamental design for an electrical circuit testing device, as shown and described.
